UNITED STATES PATENT OFFICE.

ALONZO JACKSON GRIFFIN, OF WILKES-BARRÉ, PENNSYLVANIA.

DESIGN FOR A FENCE-BAR.

SPECIFICATION forming part of Design No. 17,239, dated April 5, 1887.

Application filed November 20, 1886. Serial No. 219,534. Term of patent 7 years.

To all whom it may concern:

Be it known that I, ALONZO JACKSON GRIFFIN, a citizen of the United States, residing at Wilkes-Barré, in the county of Luzerne and State of Pennsylvania, have invented and produced a new and original Design for a Screen or Fence and the Like, of which the following is a specification, reference being had to the accompanying drawing, forming a part thereof, and in which the figure illustrates an elevation of a single bar or element of my newly-designed screen or fence.

The leading feature of my design consists of a series of two or more figures of approximately the shape of a triangle, with the apex of one triangle placed to the base of the triangle adjoining the same, the upper terminal ends of the sides of one triangle, which form the apex thereof, being formed into a compound curve and joining the inclined sides of the triangle adjoining the same.

In the drawing, A B designate the figures of approximately the shape of a triangle, and with the apex *a* of the figure B placed to the base of the figure A. The inclined converging sides *c c'* of the triangular figures are curved upon themselves at *d* and again at *e*, where they join the lower ends of the corresponding sides of the figure A adjacent thereto. These curves *d e* are of the nature of a continuous compound curve, and they are projected above the base of the figure A and between the con-

verging sides *c c'* therof. The compound curve *d e* of one inclined side, *c*, of the figure B is disposed on one side of the vertical longitudinal axis of the figure A, and the corresponding curve *d e* of the other side, *c'*, is disposed on the opposite side of the said axis. These compound curves of the converging sides *c c'* of one figure, as B, are out of contact with each other and with the sides *c c'* of the figure A, into which they are extended or projected, thereby leaving intermediate spaces, *ff'*, between the curves and the sides of the figure A.

I claim—

The design for a screen or fence herein shown and described, the same consisting of a series of two or more figures, A B, of approximately the shape of isosceles triangles placed together, with the apex of one triangle extending into the base of the triangular figure adjoining the same, the converging sides of the figure B being each formed into a compound curve, which extends between the sides of the figure A and is out of contact with the corresponding curve of the other side of the figure B.

In testimony that I claim the foregoing as my own I have hereto affixed my signature in presence of two witnesses.

ALONZO JACKSON GRIFFIN.
